WAVE FILTER

Gerhard Hässler, Berlin-Friedrichshagen, Germany, assignor to General Electric Company, a corporation of New York

Application December 3, 1937, Serial No. 177,867
In Germany December 9, 1936

3 Claims. (CL. 178—44)

In the communication field so-called wave filters are employed for filtering individual frequency channels out of a frequency mixture. These wave filters have a passage range of frequencies and one or several blocking ranges. In the blocking ranges the filters are to permit as little passage of current as possible, i. e., they must have as high attenuation as possible. In order to attain this the wave filters are so dimensioned, as is known, that in the blocking range or blocking ranges several damping poles are present and distributed in a definite manner. The word damping pole denotes a frequency at which the attenuation is very high, theoretically speaking, at which the attenuation or damping becomes infinitely high.

Such wave filters can be obtained in various ways. They may be formed of bridge circuits or equivalent circuits. In these circuits the damping poles are produced in that the bridge is perfectly balanced at these frequencies. In this way theoretically several damping poles can be produced in the blocking range or blocking ranges. But in practice it was found that where several damping poles are required, it is almost an impossibility to balance the bridge so exactly that a high damping be attained. In order to establish a perfect equilibrium of the bridge it is in fact necessary that not only the reactive components but also the resistive components be balanced.

It is known that such wave filters may also be built up by the series connection of sections or chain parts of the type known as T- or π -circuit. In this type of circuit, the various damping poles are arranged to occur in the different sections. The damping poles are produced in that at the definite frequency, the series resistance of the chain part which is to furnish the pole becomes very high, or the parallel resistance very low. This type of assembly has the advantage that it requires but a relatively small accuracy of the circuit elements.

However, it was found, that owing to the unavoidable resistances of the reactances required for the assembly of the filter, the poles of the damping curve have no longer a sufficiently high value especially when they lie in the proximity of the limiting or cut-off frequencies of the filter.

In the drawing Figure 1 illustrates a π type section of a band passed filter according to the invention, Figure 2 is the equivalent bridge circuit of the filter of Figure 1, Figure 3 is another form of the invention applied to a T type section of a filter, and Figure 4 is the equivalent bridge

circuit of Figure 3. In Figure 1 there is shown by way of example, a π type section of a band pass filter in which damping poles are produced in the upper and lower blocking ranges at the frequencies at which the fly wheel circuits in the series branch are anti-resonant. Now, if it is desired to locate these damping poles in the proximity of the limit frequencies which separate the passage range from the blocking ranges, coils of very low inductance must be employed. Since the quality of the coils, i. e., the ratio between the reactance and the effective resistance cannot be increased indefinitely, the anti-resonant impedances of the fly wheel circuits cannot be made sufficiently high to produce very pronounced damping poles.

In order to avoid this difficulty, it is proposed in accordance with the invention, that the filter sections which are to produce the damping poles lying in the proximity of the limit frequencies, be formed as bridge members which are balanced only at the pole frequencies. The behaviour of these bridge type sections in the rest of the blocking range need not be considered. The finite resistances of the anti-resonance circuits of the bridge are readily balanced at the anti-resonant frequencies by means of suitably dimensioned ohmic resistors in other parts of the bridge.

Figure 2 shows the bridge member which is the equivalent of the π -member of Figure 1. It has the same wave resistance characteristic impedance as the π -member. The energy is supplied to the terminals 1, 1' and derived at the terminals 2, 2'. The two perfectly identical fly wheel circuits S_1 and S_2 are connected to the symmetrical differential transformer U_e . If the filter consisted only of these circuit elements, it would at all frequencies be in a state of balance owing to the equality of the two fly wheel circuits, and would therefore possess a high blocking damping. But in order to have this high blocking damping acting only at the damping poles of the blocking ranges, there is placed in parallel to the fly wheel circuit S_2 , the two fly wheel circuits S_3 and S_4 connected in series. At the anti-resonant frequencies of these circuits the resistance thereof becomes very high, and the shunt to the fly wheel circuit S_2 will therefore be eliminated at these frequencies. In order to bring about at these frequencies a sufficiently perfect balance of the bridge, there is placed in parallel to the fly wheel circuit S_1 an ohmic resistor R which corresponds with the anti-resonance resistance of the fly wheel circuits S_3 and S_4 . In

order that their resistance can be reproduced, these circuits must therefore have the same resistance at the anti-resonance frequencies. This equality can be brought about by connecting the resistor r in parallel to one of the two fly wheel circuits. If particularly high requirements are demanded of the filter, the reactance of the fly wheel circuit S_4 is reproduced at the anti-resonance frequency of the fly wheel circuit S_3 by a fly wheel circuit connected in series to the fly wheel circuit S_1 . This fly wheel circuit is to be so dimensioned that at anti-resonance frequency of the fly wheel circuit S_4 , it reproduces the reactance of the fly wheel circuit S_3 , and reproduces at the anti-resonance frequency of the fly wheel circuit S_4 , the wattless component of the fly wheel circuit S_3 . This oscillatory circuit is not represented in the drawing.

The invention however, not only relates to the above-described circuits, but may also be equally well applied to circuits with series resonance circuits. Figure 3 shows a T-section, in which series resonance circuits are inserted in the series branch and parallel branch. Figure 4 shows the equivalent bridge circuit. The energy is again supplied to the terminals 1, 1'. The differential transformer U_e has the two series resonance circuits S_1 and S_2 connected thereto. S_2 has in series therewith two further series resonance circuits S_3 and S_4 having at the pole frequencies a negligibly low ohmic resistance. This low resistance is reproduced at the other side of the bridge by the ohmic resistor R . In order to render the resonance resistance equal to the two series resonance circuits a corresponding resistor r can be connected in series to the one. If an extremely accurate balance is required then in a manner analogous to the above-described example, the reactance of the series resonance circuit S_3 or S_4 which is not in resonance must likewise be reproduced on the other side of the bridge. At the terminals 2 and 2' the energy is derived from the filter.

What I claim is:

45 1. A transmission network adapted to be connected in series with a band pass filter having a pair of cut-off frequencies and large attenuation at frequencies remote from the range of frequencies between said cut-off frequencies but 50 relatively little attenuation at frequencies closely adjacent said cut-off frequencies, said network being in the form of a Wheatstone bridge having arms so constituted as to produce a substantial reactance balance at two rejection frequencies,

one of which is closely adjacent one of said cut-off frequencies and the other of which is closely adjacent the other of said cut-off frequencies, and additional resistances in said bridge so arranged as to produce a resistance balance of said bridge at said two rejection frequencies. 5

2. A transmission network adapted to be connected in series with a band pass filter having a pair of cut-off frequencies and large attenuation at frequencies remote from the range of frequencies between said cut-off frequencies but relatively little attenuation at frequencies closely adjacent said cut-off frequencies said network being in the form of a Wheatstone bridge having a parallel resonant circuit in one arm and a similar circuit shunted by a pair of series-connected parallel circuits resonant to the rejection frequencies forming a second arm of the bridge, the bridge arms being so constituted as to produce a substantial reactance balance at the two rejection frequencies, one of which is closely adjacent one of said cut-off frequencies and the other of which is closely adjacent the other of said cut-off frequencies, a resistance in shunt to the circuit in the first arm and a second resistance in shunt to one of the circuits in the second arm, said resistances producing a resistance balance 25 of said bridge at said two rejection frequencies. 15

3. A transmission network adapted to be connected in series with a band pass filter having a pair of cut-off frequencies and large attenuation at frequencies remote from the range of frequencies between said cut-off frequencies but relatively little attenuation at frequencies closely adjacent said cut-off frequencies, said network being in the form of a Wheatstone bridge having a series resonant circuit in one arm and a similar circuit having serially connected thereto a pair of parallel connected series resonant circuits resonant to the rejection frequencies forming the conjugate arm of the bridge, the bridge arms being so constituted as to produce a substantial reactance balance at the two rejection frequencies, one of which is closely adjacent one of said cut-off frequencies and the other of which is closely adjacent the other of said cut-off frequencies, a resistance in series with the circuit in the first arm and a second resistance in series with one of parallel connected series circuits in the second arm, said resistances producing a resistance balance of said bridge at said two rejection frequencies. 40 35 45 50
